UNITED STATES PATENT OFFICE

137,967

DESIGN FOR A LINEAR ACTUATOR UNIT FOR OPERATING MOVABLE PARTS OF AN AIRPLANE OR THE LIKE

William P. Lear, Piqua, Ohio, assignor to Lear
Avia, Inc., Piqua, Ohio, a corporation of Illi-
nois

Application April 1, 1943, Serial No. 109,884

Term of patent 14 years

(CL. D26—5)

To all whom it may concern:

Be it known that I, William P. Lear, a citizen of the United States of America, residing at Piqua, in the county of Miami in the State of Ohio, have invented a new, original, and ornamental Design for a Linear Actuator Unit for Operating Movable Parts of an Airplane or the like, of which the following is a specification, reference being had to the accompanying drawings, forming a part thereof.

In the drawings:

Fig. 1 is a reduced scale perspective view of a linear actuator unit for operating movable parts of an airplane or the like illustrating my new design.

Fig. 2 is a side elevational view of the linear actuator unit shown in Fig. 1, with the dot-and-dash line illustration of the control box omitted for convenience of illustration.

Fig. 3 is a left end elevational view of Fig. 2.

Fig. 4 is a top plan view of the linear actuator unit shown in Fig. 1.

Fig. 5 is a right end elevational view of Fig. 4.

The dominant features of my design reside in the portions shown in full lines.

I claim:

The ornamental design for a linear actuator unit for operating movable parts of an airplane or the like, substantially as shown and described.

WILLIAM P. LEAR.
